(57) **CLAIM**

The ornamental design for a display screen with icon, as shown and described.

DESCRIPTION

The FIGURE is a front view of a display screen with icon showing my new design.

The outer broken line shows a display screen and forms no part of the claimed design. The inner broken lines show portions of the icon that form no part of the claimed design. The white space forms no part of the claimed design.

1 Claim, 1 Drawing Sheet
